UNITED STATES PATENT OFFICE.

FRED H. VAN LOOZEN, OF CLEVELAND, OHIO.

SPPOOL OR CORD HOLDER.

1,138,812.

Specification of Letters Patent.

Patented May 11, 1915.

Application filed April 23, 1914. Serial No. 833,833.

To all whom it may concern:

Be it known that I, FRED H. VAN LOOZEN, a citizen of the United States, residing at Cleveland, in the county of Cuyahoga and State of Ohio, have invented certain new and useful Improvements in Spool or Cord Holders, of which the following is a specification.

My invention relates to improvements in spool or cord holders and is particularly designed and adapted for use in factories where it is desired to support a number of spools or balls of thread or cord for the convenient use of employees, the primary object of the invention being to prevent the theft or unauthorized removal of the spools of thread before being entirely used up, as now frequently occurs in factories, and similar places where thread is used in large quantities and a large number of employees are employed.

The primary object of the invention is to provide a generally improved spool or cord holder adapted to support a plurality or series of spools of thread in suitable position for use, the improved holder or support being provided with means whereby the spools may be automatically locked so as to prevent the removal from the spool supporting spindles while in use except by one in authority provided with a suitable key.

A further object is to provide a device of this character which will be exceedingly simple in construction, cheap of manufacture, and efficient in use.

With the above mentioned and other ends in view, the invention consists in the novel construction, arrangement, and combination of parts, hereinafter described, illustrated in some of its embodiments in the accompanying drawings, and particularly pointed out in the appended claims.

Referring to the drawings, forming a part of this specification, Figure 1, is a top plan view of a holder or support constructed in accordance with this invention, the dotted lines illustrating the position of the parts when the device is unlocked for the removal or insertion of the spools. Fig. 2, a side elevation of the same. Fig. 3, an enlarged vertical sectional view of the central bearing or spindle portions thereof. Fig. 4, a top plan view of a modified or oblong form thereof. Fig. 5, a view partly in side elevation and partly in longitudinal section. Fig. 6, an enlarged view of the rear or

locked end of the same. Fig. 7, a detail perspective view of the rear or locked end of the movable thread guide carrying member shown in Figs. 4, 5 and 6, and showing the manner of engaging or locking the thread guide carrying member by the arm of the lock.

Similar numerals of reference designate like parts throughout all the figures of the drawings.

The improved spool or cord holder comprises a spool or cord supporting and carrying holder or base member 1, provided with a plurality of spool receiving and supporting spindles 1^a, and an over-hanging movable thread guide carrying member 2, provided with a plurality or series of arms 2^a, terminating in depending thread guide loops 2^b, to receive the threads or cords 3^a, while being used from the spools 3.

When it is desired to insert or remove the spools 3, the thread guide carrying members 2, are moved to the positions indicated in the dotted lines in Figs. 1 and 4 of the drawings by the means hereinafter more fully described, thereby affording a free access to the spool carrying spindles 1^a, it being obvious that when the movable thread guide carrying members are returned to their original or normal positions as indicated in full lines in the drawings that the guide arms 2^a, will be brought immediately above the spool receiving spindles 1^a, and prevent the removal therefrom of the spindles 3.

In the form of invention shown in Figs. 1, 2 and 3 of the drawings the thread guide carrying member 2, and base or spool supporting member 1, are of round form and rotatively mounted and movable relative to each other, the spool holder or base 1, being provided with a bearing sleeve or boss 1^b, mounted upon a tubular bearing member 4, and the thread guide carrying member 2, being provided with a bearing head or boss 2^b, which head or boss 2^b, is secured to and is adapted to rotate with the tubular bearing member 4, by being secured by means of a set screw 2^d.

As a means of securing and locking the thread guide carrying member 2, in its normal or closed position as well as rotating and closing the same against the resistance of a spiral spring 5, the lower end of the tubular bearing member 4, is provided with a locking or latching arm 6, secured by means of a set screw 6^a, said arm extending outwardly

and being provided at its outer or free end with an upwardly extending portion 6^b, at one side of the spool holder or base member and being provided with a lock or latch receiving opening or recess 6^c, adapted to normally receive and contain a spring resisted locking or latching member 7, the latter, in the present instance, being a part of a suitable lock 8. The outer end portion 6^b, of the arm 6, is provided with a beveled or inclined portion 6^a, to coöperate with a similarly beveled or inclined portion 7^a, of the locking or latching member 7, whereby the latter will be pressed rearwardly against the resistance of the spring when the arm 6, and thread guide carrying member 2, are moved to their closed positions and the lock or latch member 7, will then automatically snap into engagement with the opening or recess 6^c. A guide pin 9, extending upwardly from the arm 6, and in a slot 9^a, of the base member is adapted to limit the opening movement of the arm 6, and thread guide carrying member 2, when thrown open by the spring 5. The spring 5, has one end secured in a recess 6^b, of the arm 6, the other end being secured in an opening 1^c, of the bearing sleeve or boss 1^b, of the base member.

In the form or embodiment shown in Figs. 4, 5 and 6 of the drawings the base member or spool holder 1, is of elongated box form and the thread guide carrying member 2, is in the form of a slide bar slidably mounted beneath the top portion 1^a, of the box shaped spool holder, said top portion being provided on its under side with an opening or recess 1^c, adapted to receive and contain a coiled spring 9^b, one end of which is secured to the end of the box holder and the other to the thread guide carrying member 2, so that when the member 2, and the thread guide carrying arms 2^a, and loops 2^b, are in their closed position the spring 9^b, will be under tension. The inner end of the member 2, is likewise provided with a latch or lock receiving recess 6^c, to receive and contain the locking or latching member 7, of the lock 8. The top of the box shaped spool holder 50 may be provided with a bearing standard 10, upon which may be mounted the tubular bearing member 4, of the round or circular shaped form of holder shown in Figs. 1, 2 and 3, should it be desired to support such form of holder above and use the same in connection with the form of holder just described, said bearing standard 10, taking the place of the ordinary form of standard bearing 10^a, shown in Fig. 2 of the drawings.

From the foregoing description, taken in connection with the accompanying drawings, the operation and advantages of my invention will be readily understood.

Having thus described some of the embodiments of my invention, what I claim and desire to secure by Letters Patent, is,—

1. In a spool or cord holder, a base member provided with a plurality of spool receiving spindles, a spring resisted member movable in a horizontal plane carried by said base member and provided with a plurality of arms normally overhanging said spindles and terminating in thread guide loops at the other sides thereof, and a lock carried by said base member and locking said spring resisted movable member in its normal position.

2. In a spool or cord holder, a supporting member provided with spool receiving spindles, a spring resisted thread guide carrying member rotatably carried thereby and having thread guide members normally extending over said spool receiving spindles to prevent the removal of spools therefrom, and a lock for holding said thread guide carrying member in closed relation to said spindles.

3. A spool or cord holder, comprising a stationary base member provided about its sides with a plurality of spaced spool receiving spindles, a movable member mounted thereon and provided with similarly spaced outwardly extending arms normally overhanging said spindles and terminating in depending thread guide loops at the sides of said spindles, a spring connected at one end to said base member and at the other end to said movable member, a locking device carried by said stationary member and normally holding said movable member in its closed position against the resistance of said spring, and a stop for holding said movable member in its unlocked position.

4. A spool or cord holder, comprising a stationary base member provided at its sides with a plurality of spool carrying spindles, a lock at one side of said base member provided with a spring resisted locking member, a movable member carried by said base member and provided with a plurality of outwardly extending arms normally overhanging said spindles and terminating in depending thread guide loops normally extending outside of said spools on said spool carrying spindles, a spring attached to and carried within said base member and connected to said movable member, and a lock and a spring resisted locking member within said base member and normally holding said movable member in its closed position.

In testimony whereof I have affixed my signature in presence of two witnesses.

FRED H. VAN LOOZEN.
